UNITED STATES PATENT OFFICE

2,622,545

MECHANISM FOR CONTINUOUSLY PRODUCING, DRYING, AND PACKAGING SPAGHETTI AND LIKE DOUGH-STRING ARTICLES IN EQUAL QUANTITIES OR WEIGHTS

Charles Hummel, Uzwil, Switzerland, assignor to
Gebrüder Bühler, Uzwil, SwitzerlandApplication November 20, 1947, Serial No. 787,234
In Switzerland November 28, 1946

1 Claim. (Cl. 107—4)

1

My present invention relates to improvements in mechanisms for continuously packaging spaghetti and like dough-string articles in equal quantities or weights; and the main object of my improvements is to provide means for combining the successive operations of extruding, cutting, distributing, drying and packaging on a single machine frame.

According to my present invention, the dough strings being discharged from the delivery openings of the die-expressing molding apparatus, are arranged in individual loops on spaced carrier bars which are movable in a closed track, subdivided in groups so that each group contains a definite number of looped strings of definite length (and thus of definite weight), each such group being delivered into a paper box or bag to form a package.

The mechanism according to my present invention comprises means for subdividing the dough strings into groups so that the said strings are arranged in groups on the carrier bars moving on an endless conveyer, and further means for delivering each said group of strings into a paper box or bag.

One form of mechanism for carrying out my present invention is schematically shown in the accompanying drawings, in which:

Fig. 1 shows a vertical section through the mechanism,

Fig. 2 an elevation in direction of arrow A in Fig. 1,

Fig. 3 a cross-section on line III—III of Fig. 2,

Fig. 4 a portion of Fig. 2, but in which the cut spaghetti loops have dropped from the carrier bar and their rank closed,

Fig. 5 a cross-section through the two juxtaposed conveyers at a point where the pack of spaghetti is transferred from its tray into a paper box or bag which is open at one end,

Figs. 6a and 6b show one form of die-expressing molding apparatus for subdividing the dough strings into groups, in plan view and elevation respectively,

Figs. 6c, 6d and 6e a second form thereof, in plan view, elevation and side view,

Fig. 7 shows a detail modification of Fig. 1, in which the chute for the bundled cut spaghetti loops is omitted, i. e. in which the spaghetti are delivered directly into the trays of the conveyer; and

Fig. 8 a detail modification, in which the groups of cut spaghetti loops are delivered in non-closed rank (i. e. without passing through the constricting device shown in Figs. 2-4) into the chute leading to the tray conveyer.

2

In Fig. 1, the dough is pressed from a distributor tube (1 in Fig. 6a) into a die-expressing mold 2, from which one row of dough strings *ft* (Figs. 6c, 6d) or two adjacent rows of staggered dough strings *ft* (Figs. 6a, 6b) are downwardly projected into a longitudinal guiding-trumpet 3, at the discharge end of which a first knife 4 extending longitudinally of trumpet 3 is disposed reciprocable transversely of the latter. The dough strings *ft* are picked up, approximately at their midpoint, by the bars 5, and then cut off by knife 4 so as to sit astride of the bars 5 in loops *ds*. Bars 5 are engaged at their ends or form part of a chain conveyer, of which only one chain, 6, is shown in Fig. 1, and are moved step by step, in timed relation with knife 4, by a motor M which intermittently drives a shaft 7' and two sprocket wheels 7 through a drive gear *a*—*f* (including a Geneva motion *c*, *d*). The chains 6 run over a plurality of idling rollers 8 so as to afford a length of track sufficient for drying the looped strings *ds*, and to move the bars 5 in the appropriate direction underneath the knife 4. It is to be understood that a plurality of groups of strings *ds* are mounted on the bars 5. The mechanism mentioned so far is mounted on the frame F.

As shown in Figs. 6c—e, the dough pressed from the distributing tube 1 into the die 2 and out therefrom forms single strings which are deflected into groups (of width *u* separated by interstices *v*) by the prongs or lugs 9 of a rake 10 which is secured to the underside of die 2. In the arrangement shown in Figs. 6a and 6b, however, no such deflection rake is provided for, since the strings spring from die 2' subdivided into groups (of width *u* separated by interstices *v*), the strings delivered from the rear row of perforations in die 2' being mounted on the bars 5 intermediate of the strings delivered from the front row of perforations. Since each group comprises substantially equal amounts of strings *ft*, which latter are substantially of equal diameter and length, the weights of the spaghetti in each group are substantially equal.

After the looped strings *ds* have been carried on the bars 5 by the chain conveyers 6 over a distance sufficient to become dry, a long knife 11 extending over the full width of bars 5, cuts the looped strings *ds* into two strings *ds'*. Knife 11 is fixed to one arm of two or more levers 12 which are secured to an axle 12a which in its turn is mounted rockable in frame F. The other arm of levers 12 carries a roller 12b, which is engaged by a cam 14 secured to a crankshaft 15 which is mounted rotatable in frame F and

is rotated from a motor m' through a belt a' and a pulley b' . Knife 11 thus is brought into the cutting position, i. e. rocked down onto the respective bar 5 , whenever the latter has arrived in the appointed position.

Immediately before such latter position will be reached, the lower end of the strings ds strikes against the fixed board W , and the strings are pushed together groupwise on bar 5 (Fig. 2). The group of strings arriving underneath knife 11 , still have a width u and are separated by spaces v . After the rank of the strings ds has been closed, as desired, on bar 5 , the knife 11 enters into action to cut each looped string ds into two strings ds' . The "rank-closing" gear 15 for each group of strings ds is built and operated as follows.

A connecting rod 16 is journaled at its upper end to crank-shaft 15 , and at its lower end pivoted to a swing arm 17 pinned to a rock-shaft 18 which is mounted on frame F . A link 19 at one end is pinned to rock-shaft 18 , and slotted at its other end to loosely engage a stud secured to a reciprocating rod 20 which is guided in rings W' secured to board W (Figs. 1-4). An upper and a lower axle pin 22 (Fig. 3) are mounted rotatable on board W , beside the two side walls 24 which confine each group of strings ds or ds' respectively. The said board W extends over the full length of the rods 5 , and is secured to frame F . An arm 23 at one end is pivoted to the upper and lower portion each of each side wall 24 , and at its other end is pinned to axle pin 22 . Two spaced parallel flat arms 21 also are pinned at one end to each axle pin 22 , and at their free ends are slotted to loosely engage a stud secured to the reciprocating rod 20 and projecting through the latter. When the reciprocating rods 20 are moved downward by the links 19 , the axle pins 22 are rocked through the arms 21 , and the arms 23 are swung from their position shown in Fig. 2 into that shown in Fig. 4, thus moving the two sides 24 of each group of strings ds . It is at this moment that the above mentioned cutting action of knife 11 is released. When rods 20 , subsequently, are moved upward, the groups of strings ds' (the rank of which has been closed) are released from their constricting sides, and slide through the hopper $24'$ and down the chutes 25 into the trays 26 which are mounted on a chain conveyer 27 .

The latter is moved by the chain wheels 28 which are driven from a sprocket 29 mounted on the wheel axle 30 . The trays 26 are open in front and in the rear, and the conveyer 27 is driven in step with the cutting gear $11-15$ and with the "rank-closing" gear $16-24$ described.

Another chain conveyer $27'$ to which the plates 31 having upturned rear flanges $31'$ are secured, is moved by the chain wheels $28'$ alongside the chain conveyer 27 . The conveyer $27'$ is driven through a sprocket $29'$ which is mounted on the chain-wheel axle $30'$. A stationary partition B , provided with spaced openings B' (of approximately the same width as the trays 26) is disposed intermediate of the two conveyers $27-30$ and $27'-30'$. Paper boxes or bag-like containers X are disposed on the plates 31 in abutment against the flanges $31'$ and spaced in accord with the bundles of strings ds' . When the full trays 70

26 on conveyer 27 have arrived in front of the openings B' of the stationary partition B (Fig. 5) the plungers 33 which are secured to the rod 32 , are moved in direction of the arrow shown in Fig. 5, and the bundles of strings ds' are pushed into the boxes or bags X on conveyer $27'-31'$.

In the modification shown in Fig. 7, the bundles of strings ds' are delivered directly into the trays 26 of conveyer $27-30$, i. e. the chute 25 (Fig. 1) is omitted. The conveyer in this case has to be sharply tilted as shown.

In the modification shown in Fig. 8, the cut strings ds' are held in their original arrangement, i. e. the "rank-closing" gear $16-24'$ is omitted. In this case, the cut looped strings drop down the inclined board W' , being deflected on their way into groups of width u and separated by spaces v by the deflecting ribs D .

What I claim as new and desire to secure by Letters Patent is:

Apparatus for preparing strings of dough such as spaghetti and macaroni for packaging, comprising an extrusion press die for extrusion of strings of dough, said die having rectilinearly arranged groups of extrusion openings of identical size, said groups of openings being spaced further apart than the individual openings of each group, each group containing a predetermined number of openings to produce a number of strings of predetermined weight suitable for charging a package of predetermined size, conveying means for carrying horizontally extending rods underneath said extrusion die and through a drying atmosphere, whereby the extruded strings of dough will loop over said rods in a plurality of groups of strings corresponding to said groups of extrusion openings, means for cutting said strings into equal length, means for cutting said strings on said rods in two at the looped portion of the strings upon the rods leaving said drying atmosphere whereby the strings fall from the rods, a plurality of chutes disposed to collect separately each group of strings discharged from the rods, said chutes having means for contracting laterally the ranks of strings of each group, and conveying means at the discharge end of said chutes for transporting each group of strings to a packaging place.

CHARLES HUMMEL.
